ANTON C. SCHUERMANN, OF DECATUR, ILLINOIS, ASSIGNOR TO H. MUELLER MFG. CO.,
OF DECATUR, ILLINOIS, A CORPORATION OF ILLINOIS.

COCK OR FAUCET.

1,107,452.

Specification of Letters Patent. Patented Aug. 18, 1914.

Application filed September 13, 1913. Serial No. 789,648.

To all whom it may concern:

Be it known that I, ANTON C. SCHUERMANN, a citizen of the United States, residing at Decatur, in the county of Macon and 5 State of Illinois, have invented new and useful Improvements in Cocks or Faucets, of which the following is a specification.

This invention relates to an improvement in self-closing cocks wherein the valve is operated to close with the pressure, the invention having for an object to provide a cock with a casing of a form admitting of the ready removal and replacement of the operative parts, wherein the valve seat may be 15 easily reground and the valve be repacked without removing all of the parts within the cock, wherein the valve seat serves to support the valve in position and guide the same in its movements, and wherein the casing 20 has uninterrupted passages or channels to which access may be readily gained for cleansing and other purposes.

With the above object in view, the invention also comprehends the provision of a 25 compact device, the parts of which are so peculiarly constructed and assembled that the parts may be substantially formed and economically produced, thus providing a cock which possesses great practical advantages not only in its use, but also in its manufacture.

A further object of this invention is to provide the cock with an improved handle, which may be firmly grasped in the hand, 35 when the latter is damp, the handle being of disk shape and provided with spaced notches in its edge for the reception of the fingers, and knurled or otherwise roughened projections located between the notches 40 against which are brought the portions of the fingers which do not extend into the notches.

Other objects and advantages of this invention will be brought out in the following 45 detailed description of the present embodiment of the invention, and illustrated in the accompanying drawing, in which,

Figure 1 is a vertical and central longitudinal section taken through the improved 50 cock, Fig. 2 is a horizontal longitudinal section taken centrally through the same, the valve member being shown in plan, Fig. 3 is a top plan view of the handle of the cock, Fig. 4 is a bottom plan view of the valve and 55 its operating member.

Referring to the drawing, in which like parts are designated throughout the several views by similar reference numerals, 10 designates the casing or body of the cock which is preferably of spherical form and provided with a detachable nozzle or outlet 11, threaded into the lower side of the casing. A shank 12 extends inwardly from the casing and preferably forms a part thereof, the shank terminating in an interiorly and exteriorly threaded flange 13, having its outer surface reduced to provide an exterior annular shoulder 14. A stem guide or cap 15 is threaded into the upper side of the casing 10 and carries therethrough for rotation an 60 operating stem 16, projecting at its lower end into the casing 10, and at its upper end beyond the stem guide 15. A suitable packing gland 17 is threaded over the upper end of the stem guide 15 and compresses an annular packing 18 within a recessed portion formed in the upper end of the stem guide 15, and against the operating stem 16. 65

The operating stem 16 carries an improved handle, the same being in the form of a disk 80 19 provided with a central depending boss 20 suitably apertured for the reception of the upper end of the stem 16, the latter being held within the boss by a set screw 21 passing inwardly through one side of the boss. 85 The disk 19 is provided in its periphery with a plurality of spaced notches 22 for the reception of the fingers of the operator, and providing between each pair of the notches a projection 23 forming a shoulder for engagement against the finger to insure a firm grasp upon the handle. The outer ends of the projections 23 are milled or otherwise roughened to further insure a firm grasp of 90 the handle. 95

Fixed upon the lower end of the operating stem 16 is a disk 24 engaging at its upper side against the lower end of the stem guide 15 to hold the operating stem 16 from displacement up through the stem guide. It 100 will be noted that this disk 24 is of substantially the same diameter as the diameter of the lower end of the stem guide 15, thereby admitting of the removal of the disk 24 up through the casing 10 with the stem guide 15. The disk 24 carries a cam 25 depending from the disk and having a straight side lying in parallelism with the diameter of the disk and having its opposite side formed into a pair of diverging faces of equal length 105 110

and extending inwardly to the ends of the cam. From Figs. 1 and 2 it will be noted that the cam 25 lies normally in such position that the inclined faces thereof are 5 directed away from the shank 12. A valve operating member is located within the casing and the shank and is in the form of a cylindrical block 26 having its underside grooved to form a passage 27 between the 10 nozzle 11 and the rear end of the shank 12. The upper side, at the forward end of the block 26, is cut away to provide a wall or stop 28, the inner side of which is formed into a pair of inclined faces diverging from 15 the faces upon the cam 25 and adapted to receive the cam faces thereagainst when the stem is rotated to limit such rotation. The inner wall or shoulder 29 formed by the said cutaway portion in the block 26 normally 20 receives thereagainst the straight side or face of the cam 25. A recess 30 is formed in the block 26 in its upper side and inwardly of the shoulder 29 for the reception of the rear portion of the disk 24. The shoulder 25 29 forms a stop determining the neutral position of the operating stem 16. An aperture 31 forms a passage between the channel 27 and the upper side of the block 26 at its forward end.

30 A reduced rounded valve stem 32 projects rearwardly from the block 26 and is threaded upon its extremity. An annular shoulder 33 is formed upon the stem 32 at the forward end of the threaded portion for the reception of a suitable packing of rubber, leather, or composition, housed within the recessed face of the disk 34. The disk 34 is disposed in threaded relation upon the extremity of the stem 32, and is screwed toward the shoulder 33 to bind the packing thereagainst, the disk 34 and its packing constituting a valve.

Carried about the stem 32 is a valve seat 35 in the form of an annulus or ring being 45 externally threaded at its forward end for engagement in the extremity of the shank 12. The valve seat 35 has a hollow passage-way surrounding and spaced from the stem 32. An annular shoulder is formed in the 50 periphery of the valve seat 35 midway of its ends and bears against the flange 13 of the shank to hold the valve seat in position.

The improved cock is provided with an attaching shank 36 being externally threaded 55 and provided midway of its ends with an internal shoulder 37, receiving thereagainst the inner end of a coil spring 38 extending forwardly within the attaching shank 36. The forward end of the attaching shank terminates in an enlarged head 39 loosely housing 60 the valve and having internal threads engaging with the threads upon the flange 13. The head 39 bears against the shoulder 14 of the shank 12 and binds the shanks 12 and 36 together. The spring 38 bears at its

forward end against the disk 34 and normally holds the packing against the seat 35.

In operation, the valve 34 being normally closed by the spring 38, when it is desired to open the cock the operator turns the disk handle 19, partially rotating the operating stem 16. The stem 16 turns the cam 25 to bring one end of the straight side thereof against the shoulder 29, which movement effects the sliding of the cylindrical block 26 back within the shank 12 and moves the valve away from the seat 35 against the tension of the spring 38. The lip 28 of the sliding block 26 engages the inclined faces of the cam 25 and stops the rotation of the stem 16, and prevents the cam turning a half revolution whereby it would reach dead center and necessitate the operation of the handle to close the valve. As soon as the handle is released the spring 38 expands and moves the valve against the seat 35, pushing the block 26 forwardly within the casing 10, and moving the cam 25 to its normal position. Since the cam 25 and the lip 28 are each provided with diverging inclined faces, the stem 16 is permitted movement in either direction, and will be returned, by the spring 38, to its neutral position.

In disassembling the parts of the valve it is only necessary to remove the cap 15 which carries therewith the stem 16 and the cam 25, remove the attaching shank 36 from the flange 13 whereby the spring 38 is released from the valve, and finally to unscrew the valve seat 35 from the shank 12 admitting of the drawing out of the block 26. When these parts are removed from the casing 10 and shank 12 the body of the cock presents two uninterrupted passages or channels at right angles to each other, and opening directly through the apertures in the casing. It is also observed that the valve can be readily cleansed and new parts replaced when necessary, the structure admitting of the grinding or the replacing of the valve seat and the packing of the valve itself.

In providing a handle of disk form having the knurled projections and interposed notches a handle is provided in which the fingers of the operator are received and engage against substantially flat faces or shoulders so that the hand can not slip around the handle.

Having fully described my invention what I claim as new is:

1. A self-closing cock comprising a casing having a valve seat at its inner end and an outlet nozzle at its forward end, a closely fitting movable block in the casing having a valve at its inner end and a longitudinal passage therein adapted to establish communication between the valve seat and the nozzle, a spring in the casing bearing against said block to normally seat said valve, and an operating stem rotatably mounted in the

casing having a cam upon its inner end, said block having a transverse slot in one side adapted to receive said cam whereby the rotation of said cam moves said block to unseat said valve.

2. A self-closing cock comprising a casing having a valve seat and an outlet nozzle therein, a closely fitting movable block in the casing having a valve and a longitudinal 10 passage in one side adapted to establish communication between said valve seat and said nozzle, a spring in said casing engaging said block whereby to normally seat said valve, and a stem mounted to turn in the 15 casing and having a cam upon its inner end, said block having a recess in one side receiving said cam, said recess providing a shoulder in said block and a stop opposite to said shoulder, said cam being adapted to 20 be turned within the recess whereby to bring one end of the cam against said shoulder and unseat said valve, the opposite end of said cam being adapted for engagement against said stop whereby to limit the 25 rotation of said cam.

3. A self-closing cock comprising a casing having a valve seat at its inner end and a depending nozzle at its outer end, a closely fitting movable block in the casing having 30 a valve at its inner end and provided with a longitudinal passage in its underside adapted to establish communication between

said valve seat and said nozzle, a spring engaging said block to normally seat the valve, and a stem mounted in the top of the 35 casing having a disk upon its lower end to retain the stem from displacement from the casing, said stem also having a cam depending from said disk provided with a straight side lying substantially in parallelism with the diameter of the disk and having at its opposite side a pair of diverging faces of equal length extending inwardly to the ends of the cam, said block having a recess in its upper side for the reception of said disk and a transverse slot in the bottom of said recess for the reception of said cam whereby the turning of the stem engages one end of said cam against the inner wall of said slot, the upper wall of said 45 slot comprising a pair of diverging faces of equal length extending outwardly and laterally to the ends of the wall for engagement with the diverging faces of said cam when turned whereby to limit the rotation 50 of the cam.

In testimony whereof I have hereunto set my hand in presence of two subscribing witnesses.

ANTON C. SCHUERMANN.
